P. A. DEASY.

WATER HEATER.

APPLICATION FILED DEC. 27, 1911.

1,101,485.

Patented June 23, 1914.

UNITED STATES PATENT OFFICE.

PETER A. DEASY, OF OAKLAND, CALIFORNIA, ASSIGNOR TO DEASY UTILITIES COMPANY, OF OAKLAND, CALIFORNIA, A CORPORATION OF CALIFORNIA.

WATER-HEATER.

1,101,485.

Specification of Letters Patent. Patented June 23, 1914.

Application filed December 27, 1911. Serial No. 668,042.

To all whom it may concern:

Be it known that I, PETER A. DEASY, a citizen of the United States, residing at Oakland, in the county of Alameda and State of California, have invented certain new and useful Improvements in Water-Heaters, of which the following is a specification.

This invention relates to water heaters and has special reference to a type of water heater having a central heating flue, and the principal object of the invention is to improve the general construction of heaters of this character so that differences in expansions of the parts may be accommodated.

A second object of the invention is to provide a device of this character wherein the means used to accommodate the differences in expansion will also afford increased heating surface.

A third object of the invention is to provide means for eliminating the condensation caused by the burning of gas.

With the above and other objects in view, the invention consists in general of certain novel constructions, arrangements and combinations of parts as will be hereinafter fully described, illustrated in the accompanying drawings, and specifically claimed.

In the accompanying drawings, like characters of reference indicate like parts in the several views, and Figure 1 is a vertical median section through a heater constructed in accordance with this invention. Fig. 2 is a side elevation of a heating element used herewith the same being partly in section. Fig. 3 is an enlarged detail view of a certain expansion member used in connection herewith. Fig. 4 is a section on the line 4-4, Fig. 1.

In the present embodiment of the invention there is provided a cylindrical shell 10 having on its upper end a head 11 and this shell rests on a suitable support 12.

At the lower end of the shell there is provided a frusto-conical bottom 13 corrugated in horizontal rings as can be seen by reference to Fig. 1. This bottom is securely riveted to the shell as at 14 and its upper end forms means 15 threaded interiorly for the attachment of a central flue which consists of a lower section 16, the lower end of which is screwed into the means 15, a central portion 17 which is provided with horizontally arranged corrugations as best

seen in Fig. 3, and the upper section 18 which passes through the head 11 and has fitted thereon a pipe 19. By means of this arrangement an increased heating surface is provided at the bottom while at the same time the corrugations at the bottom and sections 17 permit the uneven expansion of the shell 10 and the central flue without bringing undue strain upon the part. The central portion 17 may, if desired, be made lighter than the end sections 16 and 18 so as to more readily yield to the stresses produced by unequal expansion the corrugations serving to strengthen this section. Under the bottom 13 there is provided a frusto-conical screen 20 of open mesh metallic construction and this screen terminates at its upper end in a tubular screen 21 which passes up the central flue as can be seen by reference to the drawing.

The heater element consists of a substantially conoidal casting provided with annularly disposed shoulders 22 arranged to form a series of steps on the outside and corrugated interiorly as indicated at 23, the casing being also provided with passages 24 leading from the interior to the exterior thereof. This casting is hollow and is provided with a threaded portion 25 for the attachment of an inlet pipe 26 while from the upper end of the casting extends a pipe 27 which passes up the flue and transversely to the top thereof terminates in a downwardly extended end 28 which passes through the head 11. The pipe 26 forms a branch from a water pipe 29 which leads in through the side of the shell 10. At 30 is a third pipe by means of which the water may be drawn off as desired. Beneath the heater element there is provided a gas burner 31 of any preferred form which is supplied by gas through a pipe 32 controlled with a valve 33.

It is to be observed that when the device is started in operation a certain amount of moisture will be condensed on the heater element and will fall down into the grooved shoulders 22 where it will remain until the element has been heated sufficiently to cause re-evaporation whereupon the moisture will pass off through the flue. It will also be noted that any condensation on the bottom of the flue will accumulate on the screen 20 so that a large surface will be exposed and it will readily re-evaporate without dripping down from the screen. This screen further-

more provides means for increasing the heating surface so that the heated air passing up the flue is in intimate contact with the screen which thus absorbs a greater portion of the heat and radiates the same to the surrounding flue walls. There has thus been provided a simple and efficient device of the kind described and for the purpose specified.

10 Having thus described the invention, what is claimed as new, is:

A water heater comprising a shell, a bottom for said shell, a flue leading from said bottom vertically through said shell, a heating drum mounted in said shell beneath said bottom, a pipe leading from said drum through said flue, and a wire fabric mounted in said shell between said drum, and the

bottom of said shell and terminating in a fabric sleeve extending through said flue and surrounding the pipe passing therethrough, said bottom for said shell provided with a depending flange, said wire fabric secured to said flange for holding said wire fabric at a spaced distance from said bottom, said sleeve positioned at a spaced distance from said flue whereby moisture is spread over the heating surface and then caught by said wire fabric for vibration.

30 In testimony whereof I affix my signature in presence of two witnesses.

PETER A. DEASY.
